Primary Examiner — Ricky Pham(74) *Attorney, Agent, or Firm* — Lowe Graham Jones PLLC(57) **CLAIM**

I claim the ornamental design for a tower chopper, as shown and described.

DESCRIPTION

FIG. 1 is a top perspective view of a tower chopper, showing my new design.

FIG. 2 is a bottom perspective view of the tower chopper.

FIG. 3 is a front elevational view of the tower chopper, the rear view being identical.

FIG. 4 is a right side elevational view of the tower chopper, the left side being identical.

FIG. 5 is a top plan view of the tower chopper; and,

FIG. 6 is a bottom view of the tower chopper.

Features illustrated in broken lines form no part of the claimed design.

1 Claim, 6 Drawing Sheets**US D842,025 S**
